(57) **CLAIM**

The ornamental design for a money counter, as shown and described.

DESCRIPTION

FIG. 1 is a front, top, and right side perspective view of a money counter showing our new design;

FIG. 2 is a top plan thereof;

FIG. 3 is a front elevation thereof;

FIG. 4 is a left side elevation view thereof, the right side elevation view being a mirror image thereof; and,

FIG. 5 is a right, top, and rear perspective view thereof.

The broken lines illustrate portions of the money counter and form no part of the claimed design.

All surfaces not shown form no part of the claimed design.
